UNITED STATES PATENT OFFICE.

WILLIAM S. SOUTHWICK, OF CLINTON, MASSACHUSETTS, ASSIGNOR TO WICKWIRE SPENCER STEEL CORPORATION, OF WORCESTER, MASSACHUSETTS, A CORPORATION OF MASSACHUSETTS.

APPARATUS FOR AUTOMATICALLY FEEDING WIRE FILLING UNITS TO WIRE-FABRIC SHUTTLES.

1,415,492.

Specification of Letters Patent. Patented May 9, 1922.

Application filed March 5, 1921. Serial No. 449,835.

To all whom it may concern:

Be it known that I, WILLIAM S. SOUTHWICK, a citizen of the United States, residing at Clinton, in the county of Worcester and State of Massachusetts, have invented new and useful Improvements in Apparatus for Automatically Feeding Wire Filling Units to Wire-Fabric Shuttles, of which the following is a specification.

10 This invention relates to a method and apparatus for automatically feeding wire filling units to wire fabric shuttles.

Referring to the drawings, in which like characters indicate like parts—

15 Figure 1 in front elevation shows a portion of the right side of the framework of a wire fabric loom to which by arms is connected a weight box for the free ends of the wire fillings, the parts appearing as when seen from the front of the loom.

20 Figure 2 in rear elevation shows a part of the framework of the right side of the loom, the view being similar to Figure 1, but showing the parts as seen from the rear of the machine.

25 Figure 3 is a side elevation of the part of the mechanism for transferring the filling unit from the magazine, not shown, to the shuttle not shown carried by the lay, the girts and shafting being shown in section, the parts appearing as if viewed from the left side of the machine.

30 Figure 4 is a view similar to Figure 3, with the addition of the magazine and shuttle, the dotted and full line representation of the lever showing the position of the latter before and during the transfer movement of a filling unit from the magazine to the shuttle.

35 Figure 5 is a top plan view of the magazine and its supports, a filling unit appearing in place in the magazine.

40 Figure 6 is a perspective view of the magazine and guide for the free ends of the filling from the filling spools to the end tension members, not shown in this figure, but appearing in Figure 1, the parts appearing as if viewed from the front right hand side of the machine.

45 Figure 7 is a detail perspective view of the filling unit, the correct position of the free end of the filling being shown in full line, while the incorrect position of the free end

of the filling avoided by the construction of applicant's filling unit is shown in a dot and dash line.

50 Figure 8 is a perspective view of the lower part of the magazine construction showing the passageway for the filling unit from the magazine to the shuttle and a plate over said passageway to prevent the filling unit being thrown up out of position in its passage from the magazine to the shuttle.

55 Figure 9 is a sectional view on line 9—9 of Figure 1 looking in the direction of the arrows, showing the construction of the weight box and the parts carried thereby to support and guide the end tension members.

60 Figure 10 is a side elevation of a modified form of the bunter receiver and bunter receiver holder from that shown at the top of Figure 3.

65 Figure 11 is an end elevation of the parts shown in Figure 10.

70 Figure 12 is a top plan view of the filling guide shown in Figure 1 and the plate for supporting said guide and the weight box as shown in Figures 1 and 2.

75 Figure 13 is a diagrammatic view showing the fabric, and at the right the magazine with its guide members for the free end of the filling, the cutter for the filling, the shuttle carried by the lay, the filling unit in full line in the shuttle and dotted lines in its forward position, there also appearing at the left a representation of the position of a filling feeler and an oscillating shaft whose time of operation is controlled by the filling feeler.

80 Figure 14 is a detail perspective view of the slide for transferring the filling unit from the magazine to the shuttle.

85 Figure 15 is a similar view showing the opposite end of the slide.

90 Figure 16 is a side elevation of an end tension member, there being such a tension member connected to the free end of each filling.

95 Figure 17 is a sectional view on the line 17—17 of Figure 10 looking in the direction of the arrows showing the arrangement of the parts for connecting the modified form of bunter and bunter holder in any desired position of adjustment.

100 1 represents a portion of the right side of the framework of a wire fabric loom. 2

represents a girt, the ends of which are secured to the respective side frames 1, 1. 131 represents the lower beam of the lay, 132 the upper beam. These beams are connected at 5 their ends by bars 130, 130, the right hand bar only being shown. 133 represents the reed common in wire fabric looms. As is well known in such looms organized for weaving wire fabric with a large or stiff 10 filling, the shuttle and bars for operating the latter are carried by the lay. Prior to my invention, before the filling unit was exhausted in such looms the practice has been to stop the loom and by hand remove the 15 depleted filling unit in the shuttle and insert a fresh filling unit in the shuttle. By my invention the filling unit in the shuttle is changed automatically when the filling unit in the shuttle has been depleted to a pre- 20 determined point. Only portions or diagrammatic views of the framework and features of the loom not forming a part of my invention are shown.

Referring to Figure 3, 7 represents a casting, the lower end of which is secured to the girt 2 by bolts 8. A pintle 9 is carried by the upper end of this casting and on this pintle is loosely mounted a boss 10 formed with two lever arms 11, 12. 13 represents a 25 bunter receiver holder formed at its rear end and bottom side with a perforated ear 14 loosely arranged on the pintle or stud 15 carried on the end of the arm 12. A stud or lug 16 projects from the rear top side of the holder 13. A leaf spring 17 has its rear 30 end secured by screws 18, 18 to some convenient part of the framework. The free end of this spring engages the top of the lug 16 to yieldingly hold this lug against the front face of a lever 19. This lever at its 35 lower end is formed with a boss 20 mounted on the shaft 21 and secured thereto by a set screw 22. The shaft 21 is loosely mounted in a perforated boss or bearing 23 carried by the upper end of casting 24 secured to 40 the girt 2 by bolts 8. This shaft 21 extends across the loom, see Figure 3, showing the left end of said shaft. Power means are provided for giving the shaft a short oscillation or arc movement, when said means are 45 permitted to operate by a filling lever, not shown but situated at the left side of the loom. This arrangement allows the shaft 21 to be given its movement of oscillation in a 50 direction opposite to the movement of the hands of a watch in Figure 3, as the lay has reached its beating up position, where the shuttle is passed out of the shed and is in position for the automatic substitution of 55 a new filling unit.

In Figures 3, 10 and 11 26 represents a bunter receiver formed at the front end with inclined faces 27, 28, fashioned to be engaged by a complemental bunter member 29 se- 60 cured to the front side of the bottom beam

of the lay as the lay completes its forward movement and when the bunter receiver is in the dotted line position of Figure 3. The bunter receiver 26 is arranged in a complemental recess 30, see Figures 10 and 11. 70 In the right hand face of the bunter receiver holder 13 is a bolt 31 connected with the holder 26 which projects in a longitudinal slot 32 in the holder 13. A nut 33 upon said bolt by engaging the left face of the 75 holder binds the bunter receiver to the holder. 34 represents a perforated screw-threaded lug on the rear end of the holder 13. A set screw 35 arranged in lug 34 held in its adjusted position by a lock nut 36 is 80 arranged to engage the rear of bunter receiver 26 and with the bolt 31 and nut 33 hold the bunter receiver in any desired position of adjustment. Holder 13 and bunter receiver 26 and associate parts are shown 85 in outline in Figure 3, but in detail in Figures 10 and 11.

Referring to Figures 1, 2, 3, and 4, 38 represents a stud carried by the side frame 1 having a hub 39 loosely mounted thereon, 90 the hub being held on the stud by a cotter or other pin 40. The hub 39 upon its lower side carries a lever arm 41.

A helical spring 42 having one end secured to the lower end of the lever 41 and its 95 other end connected with the framework 1 tends to yieldingly turn the hub 39 in the direction of the movement of the hands of a watch in Figure 4. The hub 39 upon its top side carries a lever 43 which is shown 100 in Figures 1 and 2 as having beginning with the hub a substantially straight portion, then a curved portion terminating in an end portion 44 that is substantially parallel with the straight portion of the lever next to the 105 hub. This lever 43 above the hub 39 is formed with a boss 45 carrying a pintle 46. The short link 47 has its rear end arranged upon the pintle 46 and its front end arranged upon a pintle 48 carried by the end 110 of the lever 11. A nut 49 serves to hold the rear end of the lever 47 on the pintle 46. By the described construction the movement of the lever 11, to the left in Figure 3, gives a like motion to the lever arm 43 and the 115 parts to which the said arm may be connected. 50 represents a casting secured to the framework 1 on the right side of the loom by means of bolts 51. Upon the upper end of this casting is arranged a horizontal plate 52 integral with the casting 50 or secure thereto in any desired way. This plate is formed at its right end with an up-turned flange 53, see Figure 3, that serves as a stop to limit the motion of a push block 120 for the filling unit hereinafter described. 54 represents a slot formed in the bottom of this plate and open at the left hand end. This slot is parallel with the general direction of the plate and beyond the loom 125 130

and warps, but at an angle with the general direction of the weft. As shown, the upper end 44 of the lever 43 is arranged and travels in this slot. The material of the top face 5 of the plate 52 is cut away on each side of the slot 54 for a short distance laterally to form guideways 55, 55 for the flanges 56, 56 of the sliding block 57, see Figures 14 and 15. This block on its under side is 10 formed with a slot 58 registering when the parts are assembled with the slot 54. Referring to Figure 3, 61 represents a link, the right hand end of which is mounted on a pintle 60. In the vertical walls of block 15 57 on either side of slot 58 are formed apertures 59 in which is arranged the pintle 60, the other end of said link being loosely mounted upon the pintle 62 carried by the end 44 of the lever 43. The left hand end of 20 the block, see Figure 14, is extended on either side of the slot 58 to form fingers 64, 64 projecting from the end wall 65 of the block. The movement of the lever 43 and the link 61 to the right or left in Figure 4 gives a 25 corresponding motion to the block 57 and the fingers 64 and the front wall 65.

Referring to Figures 1, 9, 6, 2 and 12: 66 represents a flange or lug depending from the right side of the plate 52, see Figure 6. 30 67 represents a flange secured to the flange 66 by bolts 68. From said flange 67 extends to the right an arm shaped as an angle iron having one horizontal member 69 and a vertical member or arm 70, the latter at or 35 near its end and on its lower side formed with two holes 70^a, 70^a. The opposite side of the outer end of this arm is formed with a perforated lug 71 in which is secured a pintle 72 having thereon a rotatable spool-shaped 40 guide 73 for the filling. This guide is formed with a groove having one vertical wall 74 and an inclined wall 75 to deflect and maintain each and all the fillings passing over the guide at a fixed point, that is the 45 junction of the vertical and inclined walls 74, 75. A plate 76 has its upper end secured to the arm 70 by bolts 77, 77. As shown in Figure 1, this plate 76 is located below the guide 73. A plate 78 has its right 50 end secured to the lower end of the plate 76 by bolts 79, while its opposite end is secured to the framework 1.

Referring to Figures 1 and 9: 80 represents a horizontal series of guide pins riveted to the front face of the plate 76 below the guide 73, the number of said pins 80 corresponding to the number of filling units constituting the capacity of the magazine. As shown each guide pin 80 at a selected 60 distance from the front face of the plate 78 is reduced to form a shoulder 81. From the bottom of this shoulder the pin is enlarged to a line as 82, then reduced to a point as 83. By this construction each filling can be 65 readily inserted between the pins and against

its proper pin, the filling sliding down the incline and resting at the angle formed by said incline and shoulder 81. This permits each filling to hang vertically from the guide 73 to its hook 84, Figure 16, to which it is 70 tied, see also Figure 9 and broken line indicating position of the filling 118. As shown, each hook 84 is formed on the upper end of a rod 85 that at its lower end is secured in a weight 86. A helical spring 87 75 is loosely arranged on the rod 85 above the weight 86 and below a collar 88 loosely and slidingly arranged on said rod by resting on said spring. 90 represents a series of short vertical partitions or flanges on the 80 front face of plate 76 below the guides 80, there being a partition or flange 90 below each pin 80 located directly below said pin, see Figures 1 and 9. 91 represents a plate secured to the plate 76 below the flanges 90 85 by rivets 92. This plate 91 carries a horizontal series of flanges 93, one under each flange 90. Both sides of the under part of these fingers 93 are beveled as at 94, 95. Below each finger 93 is a plate or flange 96 90 either integral with said finger or secured in any desired way in said position on the plate 76. In effect the flange 96 constitutes a reduced continuation of the finger 93 below the bevels 94, 95. Two of the flanges 96 95 constitute a vertical chamber or guideway for a weight 86 and its associated parts.

Referring to Figure 1, a plate 97 on the front and the plate 78 on the back, together with the bottom plate not shown, constitute 100 an open box or receptacle for the weights 86 when not in use or when the free end of the filling connected with that weight unit has been cut.

Referring to Figures 1, 2, and 6: 98, 98 105 represent two plates, one arranged on the top of each side member 99 of the plate 52. Each plate 98 projects inwardly a short distance over the edge of the guideways 55, 55, and over the outer edges of the flanges 110 56, 56 of the block 57 when the latter is in place, and serve to maintain the block in place between the guideways 55, 55, and the side members 99 of plates 98 as a guide or raceway. Cap screws 100 passing 115 through ears 101 positioned on the top of said plates 98, 98, and passing through said plates into the side members 99, 99 of the plate 52, secure said ears 101 and plates 98 in place on side members 99 of said plate 120 52. The material of the front ears 101 is extended upward a short distance as 102, then inward a short distance, then upward to form the front wall 104 of the magazine 103. In a similar manner the material of 125 the rear ears 101 is extended upward to form the rear wall 105 of the magazine.

Referring to Figures 5 and 6: On the left side of the magazine the walls 104, 105 are separated to give access to the chamber of 130

the magazine, while at the right side of the magazine the walls 104, 105 are separated a slight distance to form a slot 106 through which the free end of the wire filling passes 5 from the filling unit to the spool 73 and hooks 84. But three filling units are shown in the magazine, see Figure 6, and these are separated from one another to avoid confusion of lines and to clearly illustrate the 10 parts. In practice of course the lowest filling unit would rest on the plates 98 which constitute the bottom of the magazine, and the remaining filling units in the magazine rest on top of one another. The front face 15 of the right hand wall 105 of the magazine near the lower end of said wall (see Figure 6) is formed with a slot 107 into which the free end of the bottom filling unit passes, as shown in broken lines in this figure, when said unit is pushed out of the magazine into the shuttle, said filling remaining in this slot until the filling is cut, when the weight unit of that filling will draw out the filling from the magazine and said slot as 20 the weight drops into the weight box, shown in Figure 1. This weight mechanism is broken away in two points in Figure 1 to save space on the drawings, the dropping space for the weights 86 in the 25 operative construction being sufficient to draw the filling when it is severed not only from the slot 107, but away from the spool guide 73. As clearly shown in Figure 5, the inner surface of the front wall 104 is formed 30 with a flat face 108 terminated in a shoulder 109, forming a notch, while the members of the rear wall are formed as a rectangle. As shown in Figure 8, the lower part of the middle member of the rear wall 105^a in Figure 8 is cut away to form a passageway 110 for the filling unit from the magazine to the shuttle. Ears 111, 111 projecting from said wall on either side of said passageway, support a horizontal plate 112, projecting 35 above said passageway over the path of the passageway of the filling unit from the magazine to the shuttle. This plate 112 prevents the filling units being pushed up out of their proper path during the transfer from the 40 magazine to the shuttle. An arrow in Figure 8 indicates the direction in which the filling unit is pushed out from the magazine to the shuttle.

Referring to Figure 7, 115 represents my 45 new wire filling unit comprising a base plate 116 and its spool-shaped holder 117 for the wire filling 118. The holder is rotatably mounted on a spindle 119 carried by the base plate, the other features of the unit including a tension are not shown since not necessary in connection with the present invention of which they form no part. The rear side 120 of the plate 116 is beveled at 50 each corner as at 121, 121, see Figure 5, to push aside holding members in the shuttle.

To the rear of these inclines on the right and left side the plate is formed with a notch 122 having a rear wall or shoulder 123 parallel with the face 120 and the front inclined wall 124, the latter arranged to contact with the shoulder 123 and the holding members in the shuttle to maintain the filling unit in place in the shuttle. The front walls or right angular walls 123 of the notches 122 prevent movement of the filling 75 unit toward the feed side of the shuttle or toward the magazine of the front of the lay, while the inclined walls 124 of these notches 122 permit the filling unit to be pushed against the tension of the holding members 80 in the shuttle out of the shuttle toward the rear of the loom. In the introduction of the filling unit in the shuttle the beveled corners 121, 121, see Figures 7 and 5, serve to engage the holding members of the shuttle to push them one side to permit the introduction of the filling unit, the side walls of the plate of the filling unit maintaining the holding members in the shuttle until they come to the notches 122 which they 85 enter automatically either by means of springs or otherwise.

The front corners 125, 126, of this plate are respectively beveled and rounded off, leaving a short front straight face 127, the 95 right hand of this face 127 being extended beyond the face 126 to form a blocking point or hook-shaped member 128, forming a notch 129 between said hook-shaped member 128 and the face 126, see Figure 7. 100

Referring to Figures 5, 6 and 7: In placing the filling unit 115 in the magazine 103, the rear part 120 of the plate 116 is placed against the front face of the rear wall 105^a with the right and left faces of the plate 105 against respectively the inside faces of the vertical walls 105 and 105^a. This positioning brings the face 127 of the plate 116 against the rear face 108 of the vertical plate 104, and brings the point 128 of the plate 116 in proper position against the shoulder 109 of the front plate 104. The fit between the parts of the plate 116 and the complementary parts on the inner walls of magazine is loose enough to permit the plate 116 and its wire filling holder to slide easily up and down along the walls of the magazine without binding; said fit should be snug enough to prevent the plate turning in the magazine and particularly to keep the point 120 of the plate 116 against the shoulder 109, in order to maintain the wire filling 118 on the notch 129 in front of or to the right of the point 128, as shown in full lines in Figures 6 and 7, and to prevent said filling from going to the left of the notch 128 and from dropping over the face 127 of the plate, as indicated in broken line in Figure 7. This construction and proper position of the wire filling in a magazine is important to keep 130

the wire filling in place in the magazine and insure its entering the slot 107, Figure 6, at the proper time and in the proper way, since, as is well known to those skilled in the 5 wire fabric weaving art, wire filling has a perverse propensity of taking undesired positions and holding such positions when once reached.

Referring to Figures 3 and 4, a lay 130 is 10 shown in position in said figure in elevation, 131 representing the bottom beam of the lay, 132 the upper beam, and 133 the reed usual in wire fabric looms. The operating mechanism of the lay and other parts of the loom 15 are not shown, as they may be of the usual form, and in any event are no part of the invention set forth in this application.

In Figure 13 there is represented diagrammatically the lay 130, the wire filling 118, the 20 shuttle 134, parts of the two shuttle-operating bars 135, 136 carried by the lay, the filling unit 115 in full lines in the shuttle and in the magazine but in dotted lines at the left at its advanced position when the lay 25 beats up the weft. There is further diagrammatically shown in this figure a filling feeler 137 to engage the filling in the filling unit and operate when the filling is reduced to a predetermined point. This position of the 30 filling feeler permits the mechanism operated by the loom to rock the shaft 21. This rocking action of the shaft 21 occurs after the lay has started to move rearwardly from its front position and closes down the arm 35 19, see Figure 3, dropping the bunter 26 into its dotted line position, or in position to be engaged by the complementary bunter member 29 on the front of the lay at the next forward movement of the latter. During said 40 rearward movement of the lay the shuttle 134 is passed from left to right through the shed to the right side of the loom, and as the lay completes the next forward movement to beat up the last placed filling, the member 29 45 on the lay, as stated, near the end of the movement of the lay engages the bunter 26 and by means of the connecting lever arms 11, link 47, lever 43 and links 61, moves the block 57, Figures 3, 4, and 14, from its inoperative position shown in full lines in Figure 50 3 and dotted lines at the right of Figure 4, to the limit of the stroke to the left or to the full line position shown in Figure 4. As the lay completes its said forward movement 55 and the block 57 is operated, the shuttle is positioned by the lay, as shown in Figure 4, so that as the block 57 moves to the left, in Figure 4, and engages the bottom filling unit 115 of the stack of filling units in the magazine, it pushes said bottom filling unit out of the magazine, under the plate 112, and into the shuttle 134, Figures 4 and 13, to a predetermined position where the yielding holding members in the shuttle snap into or engage the notches 122 in the plate 116. There-

after the block 57 and the levers and parts connected therewith are returned to their respective inoperative positions by the action of the spring 42, see Figure 4. The action of the block 57 in pushing the filling unit 70 into the shuttle causes that filling unit to push through the shuttle and out of the rear side thereof the spent filling unit. The inclined faces 124 of the notch 122 permit such continued movement of the filling unit out 75 of the shuttle, while, as stated, the shoulder 123 of said notch prevents movement of the unit in the shuttle toward the front of the lay. The filling units thus ejected from the shuttle drop into a chute or any other desired receptacle not shown.

Referring to Figures 1 and 16, the collar 88 can slide on the rod 85. When the parts are in position as shown in Figure 1 the upper end of the collar 88 engages the inclined 85 faces 94, 95 of the particular flanges 96, 96 constituting the guideway for its associated weight 86. Any undue strain on a particular filling 118 will pull the rod 85 through the collar 88, the latter being held against 90 the inclined faces 94, 95, against the tension of the spring 87, thus avoiding breakage, the spring 87 assisting the weight 86 and its associated parts to return to their inclined position after the said strain has ceased. 95

Referring to Figure 8 it will be noted that the walls of the magazine opposite the slot 106, that is, the walls or plates 105^b and 108, do not meet, but are separated, and such separation is sufficient to permit the fingers 100 of the operator to be inserted in the passageway thus formed to hold the filling unit and lower it and properly place it in the magazine either upon the plates 98 at the bottom of said magazine, (see Figures 1 and 6), or 105 upon another filling unit, (see Figure 4).

I claim:

1. A bunter for a wire fabric loom comprising a holding member formed upon its rear end with a pivoted part, a stud, a perforated lug, the forward part of said member being formed with guideways and a longitudinal slot, a bunter part arranged in said ways and formed with a slot, a bolt arranged in said slots for locking the bunter 110 part to said ways at any desired position of adjustment, a set screw arranged in said perforated lug to engage the rear end of said bunter part, the forward free end of said bunter part being engaged by the front 115 side of the lay beam.

2. In a loom for weaving wire fabric, a lay, a shuttle carried thereby, a magazine to the front of the lay constituted to hold a series of filling units, means associated 125 with each unit to yieldingly resist the unwinding of its filling, a slot on one side of said magazine, a notch in the wall of said magazine near its lower end connecting with the said slot, a series of filling units in said 130

chamber, the free end of each filling passing through the said slot, a tension connected to the end of each filling, a guide for said fillings between said slot and said tension, 5 means for keeping said tension separated, means for transferring the filling unit from the magazine to the shuttle, the free end of each filling automatically passing from said slot into said notch, co-operating parts upon 10 said units and said magazine to maintain said units in a predetermined path in their passage through and out of said magazine.

3. In combination, a magazine comprising vertical side walls arranged to form a chamber open at the top and bottom, a slot extending from the top to the bottom of one 15 wall of said chamber, a notch in the wall of said chamber near the delivery end thereof communicating with said slot, means on an inner wall of said chamber to insure the filling unit being inserted in a predetermined position and to insure the passage of said unit through said chamber without turning, a rib on an inner surface of said chamber, 20 the front and back walls of said chamber at their base being open to form a passageway, a driver member arranged to be reciprocated across the delivery end of said passageway, complementary parts on said driver 25 member and the walls of said magazine to control the path of movement of said driver member, and means located over said passageway at the delivery end of the latter to prevent upward movement of the filling unit 30 in its transfer from the magazine to a shuttle.

4. A magazine comprising vertical side walls arranged to form a chamber open at the top, a slot extending from the top of one wall toward the bottom of said chamber 40 to form a passageway for the filling end, a notch in the wall of said chamber near the delivery end thereof, communicating with said slot, means to insure the insertion of the filling unit in a predetermined position 45 and to insure the passage of said unit through said chamber without turning, the front and back walls of said chamber at their base being open to form a passageway, and a guide member located over said passage- 50 way at the delivery end.

5. In combination, a magazine comprising upright side walls arranged to form a chamber open at the top, a slot extending from the top of one wall toward the bottom of 55 said chamber to form a passageway for the filling end, filling units therein each comprising a holder and a bobbin, the former being provided with a guide member to hold the filling end in proper position while in 60 the magazine, a holder for the free end of the filling to keep it taut, means to insure the insertion of each filling unit in a predetermined position and to insure the passage of said units through said chamber without 65 turning, the front and back walls of said chamber at their base being open to form a passageway.

In testimony whereof I have affixed my signature.

WILLIAM S. SOUTHWICK.
